CLAIM

The ornamental design of a telescoping adjustable leg, as shown and described.

DESCRIPTION

FIG. 1 illustrates a perspective view of a telescoping adjustable leg in a collapsed condition in accordance with the invention;

FIG. 2 illustrates a left hand side view of the telescoping adjustable leg of FIG. 1, the right hand side view is identical; FIG. 3 illustrates a front view of the telescoping adjustable leg of FIG. 1, the back view is identical;

FIG. 4 illustrates a top view of the telescoping adjustable leg of FIG. 1;

FIG. 5 illustrates a bottom view of the telescoping adjustable leg of FIG. 1;

FIG. 6 illustrates a perspective view of a telescoping adjustable leg in a fully extended position in accordance with the invention;

FIG. 7 illustrates a left hand side view of the telescoping adjustable leg of FIG. 6, the right hand side view is identical; FIG. 8 illustrates a front view of the telescoping adjustable leg of FIG. 6, the back view is identical;

FIG. 9 illustrates a top view of the telescoping adjustable leg of FIG. 6; and,

FIG. 10 illustrates a bottom view of the telescoping adjustable leg of FIG. 6.
